COMBINATION WASHING AND DRYING
MACHINEOtto C. Zahn, Cudahy, Wis., and Harold Zahn,
South Bend, Ind., assignors to Otto E. Zahn,
South Bend, Ind.

Application July 13, 1946, Serial No. 683,392

9 Claims. (Cl. 68—23)

1

This invention relates to improvements in washing machines, and particularly to that type of washing machine within which clothes may be washed and then spun to extract the water therefrom and to condition them for final drying.

The primary object of this invention is to provide a washing machine having a novel and simple construction and arrangement of parts, which is inexpensive to manufacture, easy to assemble, and which has comparatively few moving or controlling parts.

A further object is to provide a washing machine having a dual drive from the motor to the machine, which drive includes automatic clutches which respond to centrifugal force and to the direction of rotation of the motor to be selectively operated automatically.

A further object is to provide a washing machine which is driven by a reversible motor preferably of the constant speed type and which has drive transmitting means associated therewith adapted to operate the device at different speeds according to the direction in which the motor operates.

A further object is to provide a device with novel means for controlling the supply of water to the washing tub thereof.

A further object is to provide a washing machine having a valve element associated with the tub thereof and adapted to be opened or closed according to the direction in which the washing tub is actuated.

Other objects will be apparent from the following specifications.

In the drawing:

Fig. 1 is a vertical sectional view of the washing machine, taken on line 1—1 of Fig. 2.

Fig. 2 is a horizontal transverse sectional view taken on line 2—2 of Fig. 1.

Fig. 3 is a detail sectional view taken on line 3—3 of Fig. 1.

Referring to the drawing, which illustrates the preferred embodiment of the invention, the numeral 10 designates the supporting legs of the device, upon which is mounted a rigid platform member 12. The platform 12 forms the base for a housing 14 whose bottom 16 rests upon said platform. A suitable cover 18 is removably mounted upon the housing 14.

A bearing plate 20 is secured upon the bottom 16 of the housing centrally thereof and has a sleeve 22 projecting vertically therefrom. At its upper end the sleeve 22 mounts a bearing member 24. A vertical shaft 26 is journaled within

2

the bearing member 24 adjacent its upper end and is also suitably journaled by a bearing 28 at the lower end of sleeve 22. The shaft 26 projects above the bearing 24 and terminates adjacent the level of the top edge of the container 14. The sleeve 22 projects downwardly through the bottom 16 and the platform 12, and a nut 30 is threaded thereon to draw the bearing plate 20 against the bottom of the housing and to firmly anchor and secure the parts together. A hub 32 having a horizontal bearing surface projects upwardly from the bearing plate 20.

A sleeve 34 fits around the tubular member 22 with its lower end bearing against the upper bearing surface of the hub 32. The upper end of the tube 34 mounts a socket 36 which is pinned at 38 or otherwise secured to the upper end of the shaft 26. The tube 34 has an enlarged screw-threaded portion 40 adjacent its lower end and one or more stop means 42 adjacent the upper end of the screw portion 40. A circumferential groove is formed in an enlarged lower end portion 44 of the tube 34 to receive the bottom wall 46 of a washing tub which is fixedly anchored thereto. The washing tub has frusto-conical side walls 48 with a substantial outwardly upwardly directed taper from its bottom to its upper edge. A plurality of openings 50 are formed within the upper portion of the tub and substantially above the normal water level 52 in the tub.

An internally screw-threaded sleeve 56 of a length somewhat shorter than the length of the screw-threaded member 40 encircles and meshes with the threads of said member 40. A plurality of substantially vertical radial water agitating vanes 58 project outwardly from the threaded sleeve 56 and are so arranged and disposed that they project below the lower end of said threaded member 56. A sealing ring 60 is fixedly carried by the bottom edges of the vanes 58, said sealing ring having an inner diameter slightly larger than the diameter of the projection 44 on the tube 34 which receives the inner margin of the bottom 46 of the tub. The bottom of the tub has a plurality of circumferentially arranged openings 62 therein which are located beneath the sealing ring 60 and adapted to be closed or sealed thereby when in the full line position illustrated in Fig. 1.

50 A pulley 64, having a hub 66 which constitutes a one-way clutch, is mounted upon the lower end of the shaft 26. A second pulley 68, having a hub 70 which also constitutes a one-way clutch, is mounted on the shaft 26 below the pulley 64. 55 A collar 72 is fixed upon the lower end of the

shaft 36 and supports the hub of the lower pulley 68. Suitable hubs or spacer means provide for support of the hub of the pulley 64 upon the upper end of the hub portion of the pulley 68, and the upper part of the hub of pulley 68 is adapted to bear against a spacer element associated with the nut 30 so that the pulleys 64 and 68 are prevented from loose play longitudinally upon the shaft 26. The hubs of the pulleys 64 and 68 may be constructed as illustrated in Fig. 3 with a toothed interior peripheral surface whose teeth 74 extend longitudinally, and the surfaces 76 between which teeth are eccentric to provide a plurality of circumferentially arranged series of ways which are eccentric of the pulley and extend from the base of one tooth to the tip of the adjacent tooth. One or more rollers 78 fit in each of these ways as illustrated. The clutch construction shown is, of course, illustrative only of a one-way clutch and any other form or construction of clutch found adaptable may be used. The clutches associated with the pulleys 64 and 68 are arranged oppositely so that, when a driving connection between either of the two pulleys and the shaft 26 is effected, the other pulley will idle and be disengaged from the shaft 26.

A depending rigid support 80 is secured at its upper end to the platform 12 and has secured at 82 at its lower end a reversible electric motor 84 whose shaft or arbor 86 projects vertically and upwardly adjacent the rim or outer margin of the machine. A pulley 88 is journaled upon the motor shaft 86, being supported by a collar 88 fixed on said shaft. A belt 92 extends over the pulleys 68 and 88 for driving connection therebetween. Above the pulley 88 the shaft 86 of the motor has fixedly secured thereto a worm or screw element 94. A second and upper pulley 96 is journaled upon the shaft 86 and bears against the upper end of the worm 94. A collar 98 is fixed upon the motor shaft 86 above the pulley 96. A belt 100 forms a driving connection between the pulleys 96 and 64. An internally screw-threaded member 102, whose axial dimension is less than the worm 94, is threaded upon said worm, said nut being constructed to be of substantial weight.

Suitable controls, none of which have been shown, may be provided with the device. Such controls may include the control for the motor 84 and a control for intake and outlet lines for supplying and withdrawing water from the housing 14. Also, if desired, thermostatic means may be supplied for controlling the temperature of the water, and any other refinements and conveniences desired, and the use of which is well known in the art, may be supplied.

In the operation of the device, assuming that water at proper temperature has been fed into the housing 14 to the desired working level 52 and that soap or other cleaning material has been introduced into the device along with the insertion into the tub 48 of the clothes to be washed, the motor 84 is caused to be operated in one direction. For washing purposes the motor 84 will be rotated in such a direction that the clutch nut 102 will be urged, by its threaded engagement with the worm 94, to its lowermost position as illustrated in Fig. 1, thereby clutching or otherwise effecting a driving connection between the shaft 86 and the lower pulley 88 journaled on said shaft. At the same time the upper pulley 96 will be declutched from the shaft 86 and thereby rendered inoperative. Driving rotation of the

pulley 88 is transmitted by the belt 92 to the lower pulley 68. The clutch associated with the pulley 68 is so arranged that when the pulley 88 is clutched to the motor shaft 86, the pulley 68 will be clutched to the shaft 26 to rotate the same. At the same time any tendency of the pulley 96 to rotate with the motor shaft 86 which is transmitted by the belt 100 to the pulley 64 acts to disengage the clutch between that pulley and the shaft 26 so that no driving action occurs between the motor and the shaft 26 through the pulley 96, belt 100 and pulley 64.

The rotation of shaft 26 serves to rotate the sleeve 34 which is pinned thereto at 38 and thereby to rotate the threaded member 40 and the tub 46, 48. This rotation is in such a direction that the threaded collar 56 is urged upwardly to its dotted line position illustrated in Fig. 1, thereby spacing the sealing ring 60 above and clear of the openings 62 in the bottom 46 of the washing tub. This permits the flow of water into the tub through the openings 62 and a circulation of water between the interior of the tub and the exterior thereof for washing action upon the clothing. In this connection it will be observed that the upward movement or adjustment of the threaded sleeve 56 upon the threaded member 40 is limited by the stops 42, and thereafter the vanes 58 are caused to rotate synchronously with the shaft 26 and the sleeve 34 to agitate both the water and the clothing within the washing tub. By reason of the size of the pulley 68, the operation of the device in washing is comparatively slow as is desirable to prevent damage or injury to the clothing. Note also that the action of the rotating vanes serves to throw water radially or centrifugally and this, combined with the angle of taper of the walls 48 of the tube, permits the water to be discharged through the openings 60 without, however, permitting clothing within the tub to be expelled therefrom. In this connection the location of the openings 60 with reference to the top of the tub may be calculated properly in accordance with the speed of rotation of the device to insure against the discharge of clothing from the tub during washing.

After the washing operation has been completed, the switch controlling the motor 84 is reversed to cause operation thereof in a reverse direction. The reversal of operation causes the clutch nut 102 to travel on the worm 94 to the full line position thereof for frictional driving engagement with the pulley 96, thereby releasing the driving connection between the pulley 88 and the motor shaft 86. The driving rotation of the pulley 96 is transmitted by the belt 100 to the pulley 64 in a proper direction to engage the one-way clutch between said pulley 64 and the shaft 26. This rotates the shaft 26 and the tub and associated parts in a direction opposite the direction in which these parts rotated for the washing operation. It will be observed that the free journaling of the pulley 88, coupled with the newly established direction of rotation of the shaft 26 which disengages the clutch of the pulley 68 from operative driving relation with the shaft 26, renders the pulleys 68 and 88 inoperative. Inasmuch as the pulley 64 is smaller than the pulley 68 and assuming that the speed of the motor shaft is the same in both directions of operation, the shaft 26 and the tub will be caused to rotate at a higher speed than the same were rotated when driven through the pulley 68. The direction of rotation of the shaft 26, sleeve 34 and the worm member 40 causes the threaded sleeve

56 to be shifted downwardly to its full line position until the sealing ring 60 seats against the base 46 of the tub to close and seal the opening 62 in the base of the tub, whereupon the sleeve 56 rotates synchronously with the threaded member 40. By virtue of the increased speed of rotation of the tub in this reversed drive direction a greater centrifugal force is exerted upon the contents of the tub and the water contained within the clothing is caused thereby to be discharged through the openings 50 to which it flows by virtue of the taper of the tub wall 48. This spinning operation effectively extracts all excess water contained in the clothing so that after operation for several minutes the clothing is in a damp-dry condition comparable to that of clothing which is passed through wringer rolls to extract excess water therefrom.

It will be noted that the device comprises a very simple and compact arrangement of parts and that the parts are so arranged that very few thereof are required to move relative to their associated parts. No manual adjustment of parts beyond the possible manual reversal of the motor switch 84 is necessary, and even that operation can be omitted if a time control of any of the types well known in the art is utilized with the motor control switch. The valve operation to open and close port 62 is automatic and likewise the engagement and disengagement of the parts to effect the change in speed is automatic through the incorporation of the one-way clutches in conjunction with the pulleys 64 and 68 and through the clutch nut 102 which cooperates with the pulleys 88 and 96. Note also that the location of the tub 48 is fixed and that, except for its rotative movement, it has no free play or movement in the device. This is rendered possible by virtue of the concavo-convex shape of the tub and also by virtue of the control of the valves by said ports solely through control of the direction of rotation of the tub.

It will be understood that while the construction herein illustrated and disclosed is preferred, the invention may be embodied in other forms within the spirit of the invention and within the scope of the appended claims.

We claim:

1. A washing machine comprising a water containing housing, a tub rotatable in said housing, reversible means for rotating said tub, an aperture in said tub below the normal water level in said housing, means responsive to rotation of said tub in one direction for closing said aperture and in the other direction for opening said aperture, said tub having other apertures therein above the liquid level in said housing.

2. A washing machine comprising a housing adapted to contain water at a predetermined level, a frusto conical tub open at its large diameter upper end rotatable axially in said housing, said tub having a port in its bottom below water level, reversible means for rotating said tub, and means responsive to the direction of rotation of said tub for respectively opening and closing said port.

3. A washing machine comprising a housing adapted to contain water at a predetermined level, a frusto conical tub open at its large diameter upper end rotatable axially in said housing, said tub having a port in its bottom below water level, reversible means for rotating said tub, and means shiftable axially responsive to the direction of rotation of said tub for respectively opening and closing said port.

4. A washing machine comprising a housing adapted to contain water at a predetermined level, a frusto conical tub open at its large diameter upper end rotatable axially in said housing, said tub having a port in its bottom below water level, reversible means for rotating said tub, a pair of cooperating meshing screw threaded members, one member being rotatable with said tub, and a sealing element carried by the other member and adapted to span and seal said port in one position.

5. A washing machine comprising a housing adapted to be partially filled with water, a tub open at its top and having an outwardly upwardly flared contour rotatable in said housing and projecting above the water level therein, said tub having an inlet below water level, reversible means for rotating said tub, said means rotating said tub at a higher speed in one rotative direction than the other, and shiftable means responding to the direction of rotation of said tub for controlling said inlet to seal the same during high speed operation and open the same during reverse rotation.

6. A washing machine comprising a housing adapted to be partially filled with water, a tub open at its top and having an outwardly upwardly flared contour rotatable in said housing and projecting above the water level therein, said tub having an inlet below water level, means for rotating said tub selectively at one of two predetermined speeds and in different directions, and shiftable means responding to the direction of rotation of said tub to open said inlet during low speed operation and seal said inlet during high speed operation for centrifugally expelling water from said tub.

7. A washing machine comprising a housing adapted to be partially filled with water, a tub open at its top and having an outwardly upwardly flared contour rotatable in said housing and projecting above the water level therein, said tub having an inlet below water level, reversible means for rotating said tub, said means rotating said tub at a higher speed in one rotative direction than the other, and shiftable means responding to the direction of rotation of said tub for controlling said inlet to seal the same during high speed operation and open the same during reverse rotation, and an agitator carried by said shiftable means.

8. A washing machine comprising a housing adapted to be partially filled with water, a vertical shaft journaled in said housing, reversible means for rotating said shaft, a screw threaded member encircling and rotatable with said shaft, a tub carried by and rotatable with said shaft and having an inlet in its bottom and below water level, and an internally screw threaded member rotatably encircling and meshing with said first threaded member for limited vertical movement relative thereto, and an annular sealing member carried by said last named member and adapted to bear against the bottom of said tub to seal said inlet.

9. A washing machine comprising a housing adapted to be partially filled with water, a vertical shaft journaled in said housing, reversible means for rotating said shaft, a screw threaded member encircling and rotatable with said shaft, a tub carried by and rotatable with said shaft and having an inlet in its bottom and below water level, an internally screw threaded member rotatably encircling and meshing with said first threaded member for limited vertical movement

relative thereto, and an annular sealing member carried by said last named member and adapted to bear against the bottom of said tub to seal said inlet, and outwardly projecting vanes carried by said last named threaded member. 5
